UNITED STATES PATENT OFFICE.

HIRAM F. HOPKINS, OF NORTH GIRARD, PENNSYLVANIA.

1,071,422.

BOAT.

Specification of Letters Patent.

Patented Aug. 26, 1913.

Application filed May 10, 1912. Serial No. 686,432.

To all whom it may concern:

Be it known that I, HIRAM F. HOPKINS, a citizen of the United States, residing at North Girard, in the county of Erie and 5 State of Pennsylvania, have invented new and useful Improvements in Boats, of which the following is a specification.

This invention relates to boats and more particularly to motor or power driven boats 10 and one of the principal objects of the invention is to provide a boat of this character without keel or skeg or log, whereby the boat will respond very readily to the rudder.

A further object of the invention is to 15 provide a boat having a vertically movable propeller and rudder which will freely rise upon engaging a bottom or anything projecting above the bottom so that the propeller or rudder will not be damaged.

20 A further object of the invention is the provision of a boat of this character having a vertically movable propeller and rudder which will have means for raising and lowering the same simultaneously so that the 25 boat may be drawn up on the beach or run down the skids without damaging the propeller or rudder.

20 A further object of the invention is to 30 provide a boat wherein the propeller shaft may be raised to draw the propeller out of the water and to connect the same with a winding drum so that when the propeller and rudder are out of the water and concealed within the boat, the boat may be read- 35 ily drawn up on a beach by its own power.

40 A further object of the invention is to provide a boat of this character having a propeller which may be raised out of the water and exposed through the deck of the 45 boat so as to be readily accessible for re- pairs or for removing collected sea grass or the like.

45 Further objects of this invention will appear as the following specific description is 50 read in connection with the accompanying drawing, which forms a part of this application, and in which:

Figure 1 is a longitudinal sectional view. Fig. 2 is a top plan view. Fig. 3 is a trans- 55 verse section on the line 3—3 of Fig. 2. Fig. 4 is a similar view on the line 4—4 of Fig. 1. Fig. 5 is a detail longitudinal view showing the propeller in raised position. Fig. 6 is a transverse sectional view on the line 6—6 of Fig. 5. Fig. 7 is a longitudi- 60 nal sectional view on the line 7—7 of Fig. 2. Fig. 8 is a rear elevation. Fig. 9 is a de- 65 tail sectional view on the line 9—9 of Fig. 2 showing the brake. Fig. 10 is an enlarged detail sectional view on the line 10—10 of Fig. 2. Fig. 11 is a sectional view on the line 11—11 of Fig. 10. Fig. 12 is a detail elevation of the rudder and its associated parts and with parts broken away.

Referring more particularly to the drawing, 1 represents the hull of the vessel which may be of any suitable shape or size and which from a point intermediate its length to its stern is provided with a longitudinal channel 2 gradually increasing in depth or height from the forward to the aft portion thereof. Adjacent the stern or in the forward portion of the rear deck 3, the hull is formed with a rearwardly extending opening 4 which passes through the deck and is closed by a hatch 5. This opening communicates with the longitudinal channel 2 and has a greater width than said channel to permit the passage of the propeller, as will be hereinafter described.

Extending inwardly from the channel 2 and also forwardly is a sleeve 6 having a bearing 7 adjacent its outer end and a stuffing box 8 at its inner end. Passing through this sleeve is an engine shaft 9 which is connected to the propeller shaft 10 through a universal joint 11. The outer end of the propeller shaft carries the usual propeller 12 and a gear 13, the purpose of which will be hereinafter described. This end of the shaft is journaled in a bearing 14 pivoted between upstanding arms 15, forming a part of a bearing member 16 constructed in two parts and surrounding the lower end of the rudder shaft 17. Depending from the bearing member 16 are arms 18 between which is pivoted a connecting member 19 which takes the place of the ordinary skeg, as will be readily understood, and has its forward end pivoted in the walls of the channel 2 and immediately aft of and below the universal joint. The rudder is shown at 20 and is constructed of a frame 21 which is rigidly secured to the rudder shaft 17 and is covered by a casing 22 which forms an air 105 tight space, making the rudder buoyant. The rudder shaft 17 passes up through the channel 2 and is slidably mounted in the bearing 23 which is pivoted between the ears 24 on the deck and is constructed of 110 separate parts connected together by the yoke arms 25. Between the separate parts

of the bearing member 23, a collar 26 is rotatably mounted and provided with an internal key 27 adapted to engage the longitudinal key way 28 formed in the shaft 17. 5 This collar is provided with a lateral arm 29 which is connected to the steering rods or cables 30, as shown. Secured to the upper portion of the shaft is an adjustable collar 31 which may be adjusted upon the shafts 10 so as to limit the downward movement of the rudder and propeller and associated parts.

Secured to the bearing 14 is a cable 32 which passes up through the slot 2 and 15 through an opening in the deck over a pulley 33 and forwardly over similar pulleys 34, where its opposite end is wound around the drum 35. This drum is provided with a ratchet wheel 36 which is engaged by a 20 spring pressed pawl 37 controlled by a foot lever 38 which is connected to the pawl by a link 39; the pawl being normally held in engagement with the ratchet wheel by a spring 40. This drum is divided into separate 25 parts by a collar or annular flange 41 and wound around one portion of the drum is a flexible member 42 which is connected to the hull through a weak spring 43 having sufficient strength to maintain a tension 30 upon the cable or rope 32. The drum is operated preferably by a crank 44 and when it is rotated in the proper direction the propeller shaft, the rudder, and the rudder shaft will be raised to the position shown in 35 Fig. 5.

When the propeller is in the position shown in Fig. 5, the gear 13 is in position to be engaged by a larger gear 45 carried upon a shaft 46 slidably mounted in the 40 sleeve 47, whose rear end is pivoted in brackets 48 and whose forward end is held down against an abutment by a spring 49. The outer end of the shaft is provided with a worm 50 which meshes with a worm wheel 51 keyed upon a shaft 52, also carrying a drum 53. This drum is provided with a grooved brake rim 54 which is engaged by a flexible brake band 55 secured at one end to the hull and connected at its opposite end 45 to the off-set portion 56 of a shaft 57 which carries upon its outer end a lever 58 adapted when operated to clamp the brake band upon the brake rim. Journalized in bearings and extending transversely across and beneath the rear deck 3 is a shaft 59 provided with an operating lever 60 and a lug 61, which when the lever is operated, will raise the sleeve 47 against the tension of the spring 49 and thereby lift the worm 50 out 50 of engagement with the worm gear 51. It will, therefore, be seen that the drum may be disconnected from the propeller shaft and thus the rotation of said drum may be stopped without stopping the rotation of the 55 propeller shaft. This will be accomplished

automatically upon a reverse rotation of the propeller shaft as the drum is locked against retrograde movement by a ratchet wheel and pawl 62 and 63, respectively. Thus when the shaft 46 is rotated, the worm will turn 70 on the wheel 51 and will cause the shaft 46 to slide in the sleeve to the position shown in dotted lines in Fig. 7, thus disconnecting the gear 45 from the gear 13. A cable of any suitable sort is wound around the drum 75 53 and in order to hold this cable against displacement or accidental unwinding, I provide a spring 64 which frictionally bears against the cable and holds it against movement on the drum.

It will be readily seen how a boat of this character can travel in shallow water and through grassy stretches where a boat with a pipe, log, and skeg stationary with the bottom of the boat could not pass. This is 80 caused by reason of the fact that the propeller and rudder may be elevated so that sea weed may be removed from the propeller and the propeller and rudder being freely movable vertically, the same will give, 85 in the manner of a center board. By attaching the cable to a tree or other stationary object on shore, and elevating the rudder and propeller shaft so that the gear 13 will connect with the gear 45, the boat may 90 be drawn up on the shore under its own power and held in such position after the power is shut off by the ratchet and pawl on the drum 53. This drum and cable, together with the drum, may be utilized for lowering 95 the boat into the water.

What is claimed is:—

1. In a boat, an engine shaft, a propeller shaft universally connected thereto at one end, a rudder post, a connection between the rudder post and the opposite end of the propeller shaft, means for raising the rudder post and the connected end of the propeller shaft, and adjustable means carried by the rudder post for limiting the downward movement of the free end of the propeller shaft.

2. In a boat, an engine shaft, a propeller shaft universally connected thereto, a propeller carried thereby, a vertically movable rudder post connected to the outer end of the propeller shaft, a rudder keyed to said post, a pivotal connection between the rudder post and the boat, means to rotate the rudder post, means to raise and lower the rudder post, and adjustable means carried by the rudder post for limiting the movement of the rudder post in one direction.

3. In a boat, a winding drum mounted thereon, a shaft for driving the same, an engine shaft, a propeller shaft universally mounted thereon, and means for moving the propeller shaft out of the water and connecting it to the drum shaft.

4. In a boat, a winding drum thereon, a

shaft for driving the same, a propeller shaft, means for raising the same, means for connecting the propeller shaft to the drum shaft when raised, and means for stopping the rotation of the drum shaft independent of the propeller shaft.

5. In a boat, a winding drum thereon, a shaft for driving the same, a propeller shaft, a sliding connection between the propeller shaft and the drum shaft adapted to automatically disconnect the drum shaft from

the propeller shaft upon a retrograde movement of the propeller shaft, and hand operated means for stopping the rotation of the drum shaft independent of the propeller 15 shaft.

In testimony whereof I affix my signature in presence of two witnesses.

HIRAM F. HOPKINS.
